UNITED STATES PATENT OFFICE.

ABRAHAM S. PINKUS, OF NEW YORK, N. Y.

SCREW DRIVER.

Application filed November 3, 1925. Serial No. 66,656.

This invention relates to screwdrivers and more particularly to screwdrivers of the clutch type in which a clutch is provided for holding the screw while it is screwed into place, or for holding the screw as it is withdrawn. An object of the invention is the provision of a clutch for the screw head which may be engaged or released by the action of the fingers of the hand which operates the device, another object is to secure the automatic release of the screw from the clutch and another object is to provide means for operating the clutch by the movement of the outer sleeve relative to the handle. Other objects of the invention will appear from the following specification and the accompanying drawings, in which, Fig. 1, is a screwdriver embodying my invention, Fig. 2 corresponds to Fig. 1, with the handle shown in section, Fig. 3 is an enlarged view of the interior with certain parts shown in section, Fig. 4 is a cross-section of the handle on the line 12—12 of Fig. 3, and Fig. 5 is a cross-section of the shank on the line 13—13 of Fig. 2.

The present invention comprises a screwdriver bit with a plurality of clutch springs extending longitudinally therewith and enclosed in a tubular sleeve. The bit is movable longitudinally relative to the handle but is secured to rotate with the handle. The clutch springs do not move longitudinally relative to the handle, but the outer sleeve is movable longitudinally relative to the handle and this sleeve may rotate independently of the other parts. The relative longitudinal motion between the sleeve and the clutch springs operates the clutch and, as the sleeve is moved by a finger grip, it is apparent that the clutch is manipulated from the handle. The longitudinal motion of the bit is opposed by a spring and so arranged that when the clutch is released, the bit automatically discharges the screw. The flat end engaging the screw is up-set from the longitudinal shank which engages the handle, this end has a shoulder which, normally is engaged by the clutch members and when in this position the device is used as an ordinary screw driver.

The preferred form of my invention is shown in the drawings in which the shank is indicated by 51, the handle by 52, the fer-

rule by 53 and the finger grip by the disc 54. The end of the spring clutch members are indicated by 56 and the flat bit by 55, which is upset from the round stock 61 with a shoulder as shown. The handle 52 has moulded or otherwise secured therein the form 64 which has a square central aperture on the longitudinal centre of the handle. The stem of the bit 61 is made from round stock and at the inner end is fitted with a square sleeve 62 which is secured thereto by the pin 63. This sleeve slides in the central aperture in 64 and is projected by the spring 65. Thus the bit 61 has a longitudinal movement relative to the handle while it is rotated by the handle and has a normally projected position.

The sleeve 51 has a flange 73 at the inner end which engages the spring 72 in the hollow handle. This sleeve can thus be moved relative to the handle to release the jaws 56 of the clutch as indicated in Fig. 2 while the spring 72 tends to move the sleeve to the position which holds the clutch jaws closed.

The clutch jaws are formed from springs 66, 67, 68 and 69 which are formed in the arc of a circle as indicated in the cross-section in Fig. 5 so as to align with the tubular form of the instrument. The inner ends of these springs are turned over as indicated at 71, Fig. 3 to engage the washer 70 which is engaged by the spring 72.

In assembling it will be noted that the clutch springs are inserted in sleeve 51 from the outer end, spring 72 and washer 70 are then placed, the stem 61 of the bit is inserted from the outer end and the square block 62 is riveted to this end when it is in place. This block prevents the washer 70 and the springs 66, 67, 68 and 69 from being displaced at the inner end and the entire device is thus ready to insert in the handle where it is held by the ferrule 53 engaging the flange 73.

In this construction it should be noted that the sleeve 51 is free to rotate as well as to slide in the handle. This sleeve may, thus, be firmly held while the device is put to its intended use. Where desired the springs 66, 67, 68 and 69 may be made of a tube slit at the end to form jaws.

Having thus described my invention, I claim:

In a screwdriver of the class described, the

combination, a handle, a tubular sleeve having one end slidably inserted in said handle, a shank formed in a bit at one end and spring fingers having inturned ends adjacent said bit 5 slidably inserted with said shank in said sleeve, said spring fingers forming jaws controlled by said sleeve for holding a screw in alignment with said bit; a ferrule on said handle resisting the outward movement of

said sleeve, a spring in said handle forcing 10 said sleeve outwards and a sliding member secured to the end of said shank making a non-turning engagement with said handle whereby said bit is operated by the handle.

Signed at New York in the county of New 15 York and State of New York this 27th day of October, A. D. 1925.

ABRAHAM S. PINKUS.
